(57) **ABSTRACT**

A method for producing a mechanical locking system for a first panel and a second panel. The method includes providing a tongue, including a first locking surface, at a first edge of the first panel, forming a tongue groove, including a second locking surface, at a second edge of the second panel, the first locking surface and second locking surface are configured to cooperate for locking the first edge to the second edge in a first direction, providing a first guiding surface at the first edge and a second guiding surface at the second edge, wherein the first guiding surface cooperates with the second guiding surface during an assembling of the first edge and the second edge, and working of the first guiding surface and/or the second guiding surface to reduce the coefficient of friction between the first guiding surface and the second guiding surface and/or a surface roughness.

**METHOD FOR PRODUCING A
MECHANICAL LOCKING SYSTEM FOR
PANELS**

**CROSS REFERENCE TO RELATED
APPLICATIONS**

The present application claims the benefit of Swedish application no. 1551670-1, filed on 17 Dec. 2015. The entire contents of Swedish application no. 1551670-1 are hereby expressly incorporated by reference in their entirety.

TECHNICAL FIELD

The present disclosure relates to floorboards provided with a mechanical locking system, and a method for producing a mechanical locking system at edges of floorboards.

BACKGROUND

Panels provided with a mechanical locking device are known in the art, as evidenced by WO2014/182215 (A1). The panels are, for some materials, difficult to assemble.

SUMMARY

One object of certain embodiments of the present invention to provide an improvement over the above described technique and the known art. A specific objective of certain embodiments is to improve assembling of panels, such as floor, building or furniture panels.

At least some of these and other objects and advantages that will be apparent from the description have been achieved by embodiments of a first aspect of the invention that includes a method for producing a mechanical locking system for a first panel and a second panel, such as building panels or floor panels, wherein the method comprises:

- providing a tongue, comprising a first locking surface, at a first edge of the first panel;
- forming a tongue groove, comprising a second locking surface, preferably by mechanical cutting, at a second edge of the second panel, said first locking surface and second locking surface are configured to cooperate for locking the first edge to the second edge in a first direction;
- providing a first guiding surface at the first edge and a second guiding surface at the second edge, wherein the mechanical locking system is configured such that first guiding surface cooperates with the second guiding surface during an assembling of the first edge and the second edge; and
- working of the first guiding surface and/or the second guiding surface to reduce a coefficient of friction and/or to reduce a surface roughness.

The mechanical locking system may be produced by mechanical cutting, such as milling, preferably in a milling line. Said working of the first guiding surface and/or the second guiding surface to reduce the coefficient of friction and/or surface roughness may be made in the milling line. The mechanical cutting may result in a guiding surface with a high friction coefficient and/or a coarse surface roughness. An assembling of the first panel and the second panel that comprise guiding surfaces with a high friction coefficient or a coarse surface roughness may be difficult. The assembling may be facilitated by said working of the first and/or the second guiding surface.

2

The method for forming the second locking surface may be different from the method for working of the second guiding surface.

The method for forming the first locking surface may be different from the method for working of the first guiding surface.

The working of the first guiding surface and/or the second guiding surface may be polishing, sanding, rolling, grinding and/or pressing by, e.g., a fixed tool, such as a sliding bar or 10 pressure shoe. The fixed tool may be of metal, such as steel, and preferably comprises a surface of hard metal or diamond.

The working of the first guiding surface and/or the second guiding surface preferably reduces the surface roughness 15 within the range of about 30% to about 50%, or about 30% to about 40%. Such a decrease of surface roughness may result in a considerable reduction of the coefficient of friction. This may have the effect that the assembling of first panel and the second panel changes from being difficult to 20 easy, or for some embodiments from being impossible to easy.

The surface roughness value may be decreased from about 3 Ra to about 2 Ra. For example, the surface roughness may be decreased at least 0.5 Ra, such as at least 0.8 Ra, 25 such as at least 1 Ra. For example, the surface roughness may be decreased to a value of less than about 2.5 Ra, such as less than 2.2 Ra, such as less than 2 Ra.

The first panel and the second panel may comprise a core material comprising a polymer material.

The polymer material may be one or more of the materials:

- Vinyls, such as polyvinyl chloride and polyvinyl butyral;
- Polyolefins, such as PE and PP;
- Polyesters, including polyethylene terephthalate (PET);
- Styrenics, such as polystyrene;
- Acrylics, such as PMMA;
- Co-polymers;
- Polymer blends;

The core material may comprise a filler and/or a reinforcement material.

The reinforcement material may be arranged as a reinforcement layer extending essentially parallel to an upper surface of the first panel and the second panel, respectively. Said reinforcement layer may increase the friction and may therefore be arranged such that an outer edge of the reinforcement layer is preferably at a non-guiding surface, such as a bottom surface of the tongue groove.

The filler material may be one or more of wood fibre, preferably as dust, or chalk.

The reinforcement material may be one or more of calcium silicate, e.g., wollastonite, or glass fiber.

The working of the first guiding surface and/or the second guiding surface may be made before the forming of the tongue groove. Applying a pressure after the forming of 55 the tongue may deform the tongue groove and/or the first edge and/or the second edge.

The method may comprise forming an insertion groove, preferably by mechanical cutting, at the first edge and arranging the tongue, preferably a displaceable tongue, in the insertion groove.

The method may comprise forming the tongue, preferably by mechanical cutting, at the first edge.

The method may comprise:

- forming a locking element at the first edge or the second edge, preferably by mechanical cutting; and
- forming a locking groove at the other of the first edge or the second edge, preferably by mechanical cutting,

wherein the locking element is configured to cooperate with the locking groove for locking the first edge to the second edge in a second direction which is perpendicular to the first direction.

The tongue may be formed at the locking element or the locking groove and the tongue groove may be formed at the other of the locking element or locking groove.

One or more of the tongue, the tongue groove, the locking element and the locking groove may be formed of a core material of the first and/or the second panel.

The flexible tongue may be according to a flexible tongue described and shown in any one of WO2006/043893, WO2007/015669, or preferably FIGS. 8A-8B in WO2014/209213(A1). The entire disclosure of each of which is hereby expressly incorporated by reference herein.

The set of panels may be furniture panels.

The core may be provided with a decorative layer.

A second aspect of the invention includes a set comprising a first and a second panel produced by the method described above.

BRIEF DESCRIPTION OF THE DRAWINGS

Embodiments of the present invention will by way of example be described in more detail with reference to the appended schematic drawings, in which:

FIGS. 1A-1C show a first panel and a second panel according to an embodiment of the invention during an assembling.

FIGS. 2A-2B show a first panel and a second panel according to an embodiment of the invention during an assembling.

FIGS. 3A-3B show a first panel and a second panel according to an embodiment of the invention during an assembling.

FIGS. 4A-4B show a first panel and a second panel according to an embodiment of the invention during an assembling.

FIGS. 5A-5B show a first panel and a second panel according to an embodiment of the invention during an assembling.

FIGS. 6A-6B show a first panel and a second panel according to an embodiment of the invention during an assembling.

FIGS. 7A-7C show tools and methods according to embodiments of the invention for producing embodiments of the first guiding surface.

DETAILED DESCRIPTION

FIG. 1A-C shows an embodiment of the invention comprising an embodiment of the mechanical locking system at a first panel 1 and a second panel 2 during an assembling. A first edge of the first panel 1 comprises a tongue 30, which in this embodiment of the mechanical locking system is a flexible tongue. The tongue 30 comprises a first locking surface 22. A second edge of the second panel 2 comprises a tongue groove 10, comprising a second locking surface 23. Said first locking surface 22 and second locking surface 23 are configured to cooperate for locking the first edge to the second edge in a first direction D1, which may be in a vertical direction. The first edge comprises a first guiding surface 20 and the second edge comprises a second guiding surface 21. Said first guiding surface 20 and said second guiding surface 21 are configured such that first guiding surface 20 cooperates with the second guiding surface 21 during the assembling of the first edge and the second edge.

The mechanical locking system comprises an insertion groove 31, at the first edge and a part of the flexible tongue is inserted in the insertion groove. The first guiding surface 20 is, in this embodiment, at a surface of the flexible tongue.

5 The flexible tongue is preferably displaceable in the insertion groove 31. The mechanical locking system comprises a locking element 8 at the first edge. The locking element 8 is configured to cooperate with a locking groove 7 at the second edge for locking the first edge to the second edge in a second direction (D2), which is perpendicular to the first direction (D1). The locking element 8 is preferably arranged on a locking strip 6 protruding from the first edge and the locking groove 7 is at a lower surface 43 of the second panel. FIG. 1A shows the first panel 1 and the second panel 2 at an initial position. The first panel 1 and the second panel 2 are during the assembling displaced vertically relative each other in the first direction D1, as shown in FIG. 1B, such that the first guiding surface 20 and second guiding surface 21 cooperate with each other. The flexible tongue 30 will, in 10 this embodiment, be displaced into insertion groove 31 and spring back to a locked position which is shown in FIG. 1C. The first locking surface 22 and the second locking surface 23 cooperate with each other in the locked position. The flexible tongue 30 may be according to a flexible tongue described and shown in any one of WO2006/043893, WO2007/015669, or preferably FIGS. 8A-8B in WO2014/209213(A1).

FIG. 2A-B shows an embodiment of the invention comprising another embodiment of the mechanical locking system at a first panel 1 and a second panel 2 during an assembling. The mechanical locking system comprises a locking element 8 at the first edge of the first panel 1. The locking element is configured to cooperate with a locking groove 7 at the second edge of the second panel 2 for locking the first edge to the second edge in the second direction (D2).

30 The locking element 8 is preferably arranged on a locking strip 6 protruding from the first edge and the locking groove is at a lower surface 43 of the second panel. An outer edge of the locking strip 6 comprising a tongue 30 configured to cooperate with a tongue groove 10 at the second edge. An upper edge of the tongue 30 comprising a first guiding surface 20 and a lower surface of a lower lip of the tongue groove 10 comprises a second guiding surface 21. An upper edge of the locking element 8 may comprise a fifth guiding 35 surface 28 and a lower lower edge at the opening of the locking groove 7 may comprise a sixth guiding surface 29. The tongue 30 and the tongue groove 10 are preferably formed of a core material of the first panel 1 and the second panel 2, respectively. The first panel 1 and the second panel

40 2 are during the assembling displaced vertically relative each other in the first direction D1, as shown in FIG. 2A, such that the first guiding surface 20 and second guiding surface 21 cooperate with each other. The fifth guiding surface 28 may cooperate with the sixth guiding surface 45 50 55 during the assembling. The first panel 1 and the second panel 2 are shown in a locked position in FIG. 2B. A first locking surface 22 of the tongue 30 and a second locking surface 23 of the tongue groove 10 cooperate with each other in the locked position.

60 FIG. 3A-B shows an embodiment of the invention comprising another embodiment of the mechanical locking system at a first panel 1 and a second panel 2 during an assembling. The mechanical locking system comprises a locking element 8 at the first edge of the first panel 1. The locking element 8 is configured to cooperate with a locking groove 7 at the second edge of the second panel 2 for locking the first edge to the second edge in the second direction D2.

The locking element 8 is preferably arranged on a locking strip 6 protruding from the first edge and the locking groove 7 is at a lower surface 43 of the second panel. An inner edge of the locking element 8 comprising a first tongue 30 configured to cooperate with a first tongue groove 10 at an inner edge of the locking groove 7 for locking the first edge to the second edge in the first direction D1. An upper edge of the first tongue 30 at the locking element 8 comprising a first guiding surface 20 and a lower surface of a lower lip of the tongue groove at the locking groove comprises a second guiding surface 21. An upper most edge of the first panel and an upper most edge of the second panel may be in contact at a joint plane 33. The second edge comprises a second tongue 32 at the joint plane and the first edge comprises a second tongue groove 11 at the joint plane. The second tongue 31 and the second tongue groove 11 at the joint plane 33 are configured to cooperate for locking the first edge to the second edge in the first direction D1. The first tongue 30 at the locking element and the second tongue 31 at the joint plane 33, respectively, and the first tongue groove 10 at the locking groove and the second tongue groove 11 at the joint plane, respectively, are preferably formed of a core material of the first panel 1 and the second panel 2, respectively. The first panel and the second panel are, during the assembling, displaced vertically relative each other in the first direction D1, as shown in FIG. 3A, such that the first guiding surface 20 and the second guiding surface 21 cooperate with each other. The first panel and the second panel are shown in a locked position in FIG. 3B. A first locking surface 22 of the first tongue 30 and a second locking surface 23 of the first tongue groove 10 cooperate with each other in the locked position; a third locking surface 24 of the second tongue and a fourth locking surface 25 of the second tongue groove cooperate with each other in the locked position.

FIG. 4A-B shows an embodiment of the invention comprising another embodiment of the mechanical locking system at a first panel 1 and a second panel 2 during an assembling. The mechanical locking system comprises a locking element 8 at the first edge of the first panel 1. The locking element 8 is configured to cooperate with a locking groove 7 at the second edge of the second panel 2 for locking the first edge to the second edge in the second direction D2. The locking element 8 is preferably arranged on a locking strip 6 protruding from the first edge and the locking groove 7 is at a lower surface 43 of the second panel. An inner edge of the locking element 8 comprising a first tongue 30 configured to cooperate with a first tongue groove 10 at an inner edge of the locking groove 7 for locking the first edge to the second edge in the first direction D1. An upper edge of the first tongue 30 at the locking element comprising a first guiding surface 20 and a lower surface of a lower lip of the first tongue groove 10 at the locking groove comprises a second guiding surface 21. An upper most edge of the first panel and an upper most edge of the second panel may be in contact at a joint plane 33. The first edge comprises a second tongue 31 at the joint plane and the second edge comprises a second tongue groove 11 at the joint plane. The second tongue 31 and the second tongue groove 11 at the joint plane are configured to cooperate for locking the first edge to the second edge in the first direction D1. An upper edge of the second tongue 31 at the joint plane comprising a third guiding surface 26 and a lower surface of a lower lip of the second tongue groove 11 at the joint plane comprises a fourth guiding surface 27. The first tongue 30 at the locking element and the second tongue 31 at the joint plane, respectively, and the first tongue groove 10 at the locking groove and the second tongue groove 11 at the joint plane, respec-

tively, are preferably formed of a core material of the first panel 1 and the second panel 2, respectively. The first panel and the second panel are, during the assembling, displaced vertically relative each other in the first direction D1, as shown in FIG. 4A, such that the first guiding surface 20 and the second guiding surface 21 cooperate with each other, and such that the third guiding surface 26 and the fourth guiding surface 27 cooperate with each other. The first panel and the second panel are shown in a locked position in FIG. 4B. A first locking surface 22 of the first tongue 30 and a second locking surface 23 of the first tongue groove 10 cooperate with each other in the locked position; a third locking surface 24 of the second tongue and a fourth locking surface 25 of the second tongue groove cooperate with each other in the locked position.

FIG. 5A-B shows an embodiment of the invention comprising another embodiment of the mechanical locking system at a first panel 1 and a second panel 2 during an assembling. The mechanical locking system comprises a locking element 8 at the first edge of the first panel 1. The locking element 8 is configured to cooperate with a locking groove 7 at the second edge of the second panel 2 for locking the first edge to the second edge in the second direction D2. The locking element 8 is preferably arranged on a locking strip 6 protruding from the first edge and the locking groove 7 is at a lower surface 43 of the second panel. An inner edge of the locking element 8 comprising a tongue 30 configured to cooperate with a tongue groove 10 at an inner edge of the locking groove 7 for locking the first edge to the second edge in the first direction D1. An upper edge of the tongue 30 at the locking element 8 comprising a first guiding surface 20 and a lower surface of a lower lip of the tongue groove 10 at the locking groove 7 comprises a second guiding surface 21. An upper most edge of the first panel and an upper most edge of the second panel may be in contact at a joint plane 33. The tongue and the tongue groove are preferably formed of a core material of the first panel 1 and the second panel 2, respectively. The first panel and the second panel are, during the assembling, displaced vertically relative each other in the first direction D1, as shown in FIG. 5A, such that the first guiding surface 20 and the second guiding surface 21 cooperate with each other. The first panel and the second panel are shown in a locked position in FIG. 5B. A first locking surface 22 of the tongue and a second locking surface 23 of the tongue groove cooperate with each other in the locked position.

FIG. 6A-B shows an embodiment of the invention comprising another embodiment of the mechanical locking system at a first panel 1 and a second panel 2 during an assembling. The mechanical locking system comprises a locking element 8 at the second edge of the second panel 2. The locking element is configured to cooperate with a locking groove 7 at the first edge of the first panel 2 for locking the first edge to the second edge in the second direction D2. The locking element 8 is preferably arranged on a locking strip 6 protruding from the second edge and the locking groove 7 is at a lower surface 43 of first panel. An upper edge of the locking element 8 comprising a second guiding surface 21 and a lower a lower edge at the opening of the locking groove 7 comprises a first guiding surface 20. An upper most edge of the first panel and an upper most edge of the second panel may be in contact at a joint plane 33. The first edge comprises a tongue 30 at the joint plane and the second edge comprises a tongue groove 10 at the joint plane. The tongue and the tongue groove at the joint plane are configured to cooperate for locking the first edge to the second edge in the first direction D1. The tongue and the

tongue groove are preferably formed of a core material of the first panel **1** and the second panel **2**, respectively. The first panel and the second panel are, during the assembling, displaced vertically relative each other in the first direction **D1**, as shown in FIG. 6A, such that the first guiding surface **20** and the second guiding surface **21** cooperate with each other. The first panel and the second panel are shown in a locked position in FIG. 6B. A first locking surface **22** of the tongue and a second locking surface **23** of the tongue groove cooperate with each other in the locked position.

The first and the second panels may comprise a core material comprising a polymer material.

The polymer material may be one or more of the materials:

Vinyls, such as polyvinyl chloride and polyvinyl butyral; 15 Polyolefins, such as PE and PP;

Polyesters, including polyethylene terephthalate (PET);

Styrenics, such as polystyrene;

Acrylics, such as PMMA;

co-polymers, such as co-polymers including one or more 20 of the above materials; and

polymer blends, such as polymer blends including one or 25 more of the above materials.

The core material may comprise a filler and/or a reinforcement material.

The reinforcement material may be arranged as a reinforcement layer **40** extending essentially parallel to an upper surface **42** of the first and the second panel, respectively. Said reinforcement layer may increase the friction and may therefore be arranged such that an outer edge of the reinforcement layer is preferably at a non-guiding surface, such as a bottom surface of the tongue groove.

The filler material may be one or more of wood fibre, preferably as dust, or chalk.

The reinforcement material may be one or more of calcium silicate, e.g., wollastonite, or glass fiber.

A method for producing an embodiment of a mechanical locking system for a first panel and a second panel, such as building panels or floor panels, comprises:

providing a tongue **30**, comprising a first locking surface 40

22, at a first edge of the first panel **1**,

forming a tongue groove **10**, comprising a second locking surface **23**, preferably by mechanical cutting, at a second edge of the second panel, said first and second locking surface are configured to cooperate for locking the first edge to the second edge in a first direction **D1**,

providing a first guiding surface **20** at the first edge and a second guiding surface **21** at the second edge, wherein the mechanical locking system is configured such that first guiding surface cooperates with the second guiding surface during an assembling of the first edge and the second edge

working of the first and/or the second guiding surface to reduce the coefficient of friction.

The first and/or the second guiding surface of the above described mechanical locking system preferably has a lower coefficient of friction and/or a finer surface roughness than an adjacent surface in the locking system. For example, an adjacent surface produced by the same or similar process step, such as mechanical cutting.

The mechanical locking system may be produced by mechanical cutting, such as milling, preferably in a milling line. Said working of the first guiding surface and/or the second guiding surface to reduce the coefficient of friction a surface roughness may be made in the milling line. The mechanical cutting may result in a guiding surface with a high friction coefficient and/or a coarse surface roughness.

FIG. 7A-7C shows embodiment of the working of the second guiding surface **21** by a tool **70**. The working of the second guiding surface may be a polishing, a sanding, a grinding, and/or a pressing by, e.g., a fixed tool, such as a sliding bar or pressure shoe

The fixed tool may for example reduce the surface roughness of the second guiding surface within the range of about 30% to about 50%, or about 30% to about 40%. The surface roughness value may be decreased from about 3 Ra to about

10 2 Ra. For example, the surface roughness may be decreased at least 0.5 Ra, such as at least 0.8 Ra, such as at least 1 Ra. For example, the surface roughness may be decreased to a value of less than about 2.5 Ra, such as less than 2.2 Ra, such as less than 2 Ra. Such a decrease of surface roughness may result in a considerable reduction of the coefficient of friction. This may have the effect that the assembling of first panel and the second panel changes from being difficult to easy, or for some embodiments from being impossible to easy.

The surface roughness may be measured with a diamond stylus profilometer, such as E-35B from Accretech.

An embodiment may comprise a core comprising a wood based material, such as MDF or MDF. The surface roughness value for this embodiment may be decreased from 25 about 5 Ra to about 3 Ra. For example, the surface roughness may be decreased at least 1 Ra, such as at least 1.5 Ra, such as at least 2 Ra. For example, the surface roughness may be decreased to a value of less than about 4 Ra, such as less than 3.5 Ra, such as less than 3 Ra. The working of the first guiding surface and/or the second guiding surface of this embodiment preferably reduces the surface roughness within the range of about 30% to about 50%, or about 30% to about 40%.

The method and the tool for working the first guiding surface may work the second guiding surface and an adjacent surface which may also be a guiding surface, as shown in the FIGS. 7A-7C. The tool may also have a shape configured such that only the second guiding surface is being worked (not shown). FIG. 7A shows an embodiment comprising working of the second guiding surface after the tongue groove **10** is formed. FIG. 7B shows a preferred embodiment comprising working of the second guiding surface before the tongue groove is formed. FIG. 7C shows an embodiment comprising working of the second guiding surface **21** and the second locking surface **23**, at the same time and with an embodiment of the tool **70**.

The method and the tool for working the first guiding surface, the third guiding surface or the fourth guiding surface (not shown) may be the same or similar with a shape that is adapted to the first guiding surface, the third guiding surface and the fourth guiding surface, respectively.

The fixed tool may be of metal, such as steel, and preferably comprises a surface of hard metal or diamond.

The method may comprise forming an insertion groove **20**, preferably by mechanical cutting, at the first edge and arranging the tongue **30**, preferably a displaceable tongue, in the insertion groove **20** by an inserting machine preferably arranged in the milling line.

The method may comprise forming the tongue, preferably by mechanical cutting in the milling line, at the first edge.

The method may comprise:

- forming a locking element **8** at the first or the second edge, preferably by mechanical cutting in the milling line; and
- forming a locking groove **7** at the other of the first or the second edge, preferably by mechanical cutting in the milling line, wherein the locking element is configured

to cooperate with the locking groove for locking the first edge to the second edge in a second direction D2 which is perpendicular to the first direction D1.

The method may comprise forming, preferably in the milling line, the tongue at the locking element or the locking groove and the tongue groove at the other of the locking element or locking groove.

The method may comprise forming, preferably in the milling line, one or more of the tongue, the tongue groove, the locking element and the locking groove of a core material of the first and/or the second panel.

Any embodiment of the mechanical locking system described above may be produced by embodiments of the method described above.

Embodiments

1. A method for producing a mechanical locking system for a first panel and a second panel, such as building panels or floor panels, wherein the method comprises:

providing a tongue (30), comprising a first locking surface (22), at a first edge of the first panel (1);

forming a tongue groove (10), comprising a second locking surface (23), preferably by mechanical cutting, at a second edge of the second panel, said first locking surface and second locking surface are configured to cooperate for locking the first edge to the second edge in a first direction (D1);

providing a first guiding surface (20) at the first edge and a second guiding surface (21) at the second edge, wherein the mechanical locking system is configured such that first guiding surface cooperates with the second guiding surface during an assembling of the first edge and the second edge; and

working of the first guiding surface and/or the second guiding surface to reduce a coefficient of friction between the first guiding surface and the second guiding surface and/or to reduce a surface roughness of the worked guiding surface(s).

2. The method as in embodiment 1, comprising working the second guiding surface, wherein the method for forming the second locking surface (23) is different from the method for working of the second guiding surface (21).

3. The method as in embodiment 1 or 2, comprising working the first guiding surface, wherein a method for forming the first locking surface (23) is different from the method for working of the first guiding surface (20).

4. The method as in any one of the embodiments 1-3, wherein the working of the first guiding surface and/or the second guiding surface is a polishing, a sanding, a grinding and/or pressing by, e.g., a fixed tool, such as a sliding bar or pressure shoe.

5. The method as in any one of the embodiments 1-5, wherein the first panel and the second panels comprises a core material comprising a polymer material, such as a thermoplastic material.

6. The method as in embodiment 5, wherein the core material comprises a filler and/or a reinforcement material.

7. The method as in any one of the embodiments 1-6, wherein the working of the guiding surface is made before the forming of the tongue groove.

8. The method as in any one of the embodiments 1-7, wherein the method comprises forming an insertion groove (31), preferably by mechanical cutting, at the first edge and arranging the tongue (30), preferably a displaceable tongue, in the insertion groove (20).

9. The method as in any one of the embodiments 1-7, wherein the method comprises forming the tongue, preferably by mechanical cutting, at the first edge.

10. The method as in any one of the preceding embodiments, wherein the method comprises:

forming a locking element (8) at the first edge or the second edge, preferably by mechanical cutting; and forming a locking groove (7) at the other of the first edge or the second edge, preferably by mechanical cutting, wherein the locking element is configured to cooperate with the locking groove for locking the first edge to the second edge in a second direction (D2) which is perpendicular to the first direction (D1).

11. The method as in embodiment 10, wherein the tongue is formed at the locking element or the locking groove and the tongue groove is formed at the other of the locking element or locking groove.

12. The method as in any one of the preceding embodiments, wherein one or more of the tongue, the tongue groove, the locking element and the locking groove are formed of a core material of the first and/or the second panel.

13. The method as in any one of the preceding embodiments, wherein the working of the first guiding surface and/or the second guiding surface reduces the surface roughness value within the range of about 30% to about 50%, or from about 30% to about 40%.

14. The method as in any one of the preceding embodiments, wherein the working of the first guiding surface and/or the second guiding surface reduces the surface roughness to a value of less than about 2.5 Ra, such as less than 2.2 Ra, such as less than 2 Ra.

15. The method as in any one of the preceding embodiments, wherein the working of the first guiding surface and/or the second guiding surface decreases the surface roughness value at least 0.5 Ra, such as at least 0.8 Ra, such as at least 1 Ra.

16. The method as in any one of the preceding embodiments, wherein the working of the first guiding surface and/or the second guiding surface reduces the surface roughness value from about 3 Ra to about 2 Ra.

The invention claimed is:

1. A method for producing a mechanical locking system for a first panel and a second panel, wherein the first and second panels comprise a core material comprising a thermoplastic material, wherein the method comprises:

providing a tongue, comprising a first locking surface, at a first edge of the first panel;

forming a tongue groove, comprising a second locking surface, at a second edge of the second panel, said first locking surface and second locking surface are configured to cooperate for locking the first edge to the second edge in a first direction;

providing a first guiding surface at the first edge and a second guiding surface at the second edge, wherein the mechanical locking system is configured such that first guiding surface cooperates with the second guiding surface during an assembling of the first edge and the second edge; and

working of the first guiding surface and/or the second guiding surface, to reduce a surface roughness of the worked guiding surface(s), wherein the working is performed by a fixed tool; and

working, with the fixed tool, of an adjacent surface which is adjacent to the second guiding surface, while working the first guiding surface and/or the second guiding surface with the fixed tool.

11

2. The method as claimed in claim 1, comprising working the second guiding surface, wherein the method for forming the second locking surface is different from the method for working of the second guiding surface.

3. The method as claimed in claim 1, comprising working the first guiding surface, wherein a method for forming the first locking surface is different from the method for working of the first guiding surface.

4. The method as claimed in claim 1, wherein the working of the first guiding surface and/or the second guiding surface is a polishing, a sanding, a grinding and/or a pressing.

5. The method as claimed in claim 1, wherein the core material comprises a filler and/or a reinforcement material.

6. The method as claimed in claim 1, wherein the working of the first guiding surface or the second guiding surface is made before the forming of the tongue groove.

7. The method as claimed in claim 1, wherein the method comprises forming an insertion groove, at the first edge and arranging the tongue, in the insertion groove.

8. The method as claimed in claim 1, wherein the method comprises forming the tongue, at the first edge.

9. The method as claimed in claim 1, wherein one or more of the tongue, the tongue groove, the locking element and the locking groove are formed of a core material of the first and/or the second panel.

10. The method as claimed in claim 1, wherein the working of the first guiding surface and/or the second guiding surface reduces the surface roughness value within the range of about 30% to about 50%.

11. The method as claimed in claim 1, wherein the working of the first guiding surface and/or the second guiding surface reduces the surface roughness to a value of less than about 2.5 Ra.

12. The method as claimed in claim 1, wherein the working of the first guiding surface and/or the second guiding surface decreases the surface roughness value at least 0.5 Ra.

12

13. The method as claimed in claim 1, wherein the working of the first guiding surface and/or the second guiding surface reduces the surface roughness value from about 3 Ra to about 2 Ra.

14. The method as claimed in claim 1, wherein the first and second panels are building panels or floor panels.

15. The method as claimed in claim 1, wherein the fixed tool is a sliding bar or a pressure shoe.

16. The method as claimed in claim 1, wherein the working of the first guiding surface and/or the second guiding surface is a sanding, a grinding and/or a pressing.

17. The method as claimed in claim 1, wherein the adjacent surface is at a non-zero angle relative to the second guiding surface.

18. The method as claimed in claim 1, wherein the method comprises:

forming a locking element at the first edge or the second edge; and

20 forming a locking groove at the other of the first edge or the second edge, wherein the locking element is configured to cooperate with the locking groove for locking the first edge to the second edge in a second direction which is perpendicular to the first direction.

19. The method as claimed in claim 18, wherein the tongue is formed at the locking element or the locking groove and the tongue groove is formed at the other of the locking element or locking groove.

20. The method as claimed in claim 1, wherein the fixed tool works the second guiding surface and the adjacent surface at the same time.

21. The method as claimed in claim 20, wherein the adjacent surface is at a non-zero angle relative to the second guiding surface.
